CLAIM

The ornamental design for a surgical bur kit holder, as shown and described.

DESCRIPTION

FIG. 1 is perspective view of a surgical bur kit holder showing the lid in an open position with bushings seated in the circular tool-receiving apertures;

FIG. 2 is another perspective view of the surgical bur kit holder with the lid in the open position without bushings seated in the circular tool-receiving apertures;

FIG. 3 is a front elevation view of FIG. 2;

FIG. 4 is a rear elevation view of FIG. 2;

FIG. 5 is a right side elevation view of FIG. 2;

FIG. 6 is a left side elevation view of FIG. 2;

FIG. 7 is a top plan view of FIG. 2;

FIG. 8 is a bottom plan view of FIG. 2;

FIG. 9 is a perspective view of FIG. 2 with the lid in a closed position;

FIG. 10 is a bottom perspective of FIG. 9;

FIG. 11 is another perspective view of FIG. 9;

FIG. 12 is a front elevation view of FIG. 9;

FIG. 13 is a rear elevation view of FIG. 9;

FIG. 14 is a right side elevation view of FIG. 9;

FIG. 15 is a left side elevation view of FIG. 9;

FIG. 16 is a top plan view of FIG. 9; and,

FIG. 17 is a bottom plan view of FIG. 9.

The broken lines in the drawings depict portions of the surgical bur kit holder that form no part of the claimed design.
